(57) **CLAIM**

The ornamental design for a food package, as shown and described.

DESCRIPTION

FIG. 1 is a perspective view of a food package;

FIG. 2 is a front view of the food package shown in FIG. 1;

FIG. 3 is a rear view of the food package shown in FIG. 1;

FIG. 4 is a left side view of the food package shown in FIG. 1, the right side being a mirror image thereof;

FIG. 5 is top view of the food package shown in FIG. 1; and, FIG. 6 is a bottom view of the food package shown in FIG. 1. The broken line showing of oval-shaped recess is included for the purpose of illustrating environmental structure and forms no part of the claimed design.
